CLAIM

The ornamental design for a display panel with animated graphical user interface, as shown and described.

DESCRIPTION

FIG. 1 is a front view of the display panel with animated graphical user interface showing a first image according to a first embodiment of the present design;

FIG. 2 is a front view showing a second image thereof;

FIG. 3 is a front view showing a third image thereof;

FIG. 4 is a front view showing a fourth image thereof;

FIG. 5 is a front view of the display panel with animated graphical user interface showing a first image according to a second embodiment of the present design;

FIG. 6 is a front view showing a second image thereof;

FIG. 7 is a front view showing a third image thereof;

FIG. 8 is a front view showing a fourth image thereof;

FIG. 9 is a front view of the display panel with animated graphical user interface showing a first image according to a third embodiment of the present design;

FIG. 10 is a front view showing a second image thereof;

FIG. 11 is a front view showing a third image thereof; and,

FIG. 12 is a front view showing a fourth image thereof. The broken lines indicate unclaimed portions of the article that form no part of the claimed design.

The appearance of the animated graphical user interface sequentially transitions between the images shown in FIGS.

(Continued)

1-4, 5-8, and 9-12. The process or period in which one image transitions to another image forms no part of the claimed design.
